UNITED STATES PATENT OFFICE.

JAY GRANT DE REMER, OF SAN FRANCISCO, CALIFORNIA, ASSIGNOR TO SAVAGE-DE REMER CORPORATION, A CORPORATION OF NEW YORK.

REFRIGERATING APPARATUS.

Application filed November 11, 1919. Serial No. 337,152.

The invention relates to refrigerating apparatus in which separate bodies of refrigerant fluid are compressed by the action of separate bodies of compressor liquid, and 5 in which the expansion of the compressed refrigerant fluid is controlled to accomplish the desired pressure reduction.

An object of the invention is to provide a liquid sealing valve for the compressed 10 fluid.

Another object of the invention is to provide means for maintaining the liquid of the seal at the proper radial levels to accomplish the desired pressure reduction.

15 A further object of the invention is to provide a refrigerating apparatus which does not embody valves, stuffing boxes, pistons, etc.

The invention possesses other advantageous features, some of which, with the foregoing, will be set forth at length in the following description, where I shall outline in full, that form of the apparatus which I have selected for illustration in the drawings 25 accompanying and forming part of the present specification. In said drawings, I have shown one specific embodiment of my invention, but it is to be understood that I do not limit myself to such form, since the 30 invention, as expressed in the claims, may be embodied in a plurality of forms.

Referring to the accompanying drawings:

Figure 1 is an elevation of the apparatus of my invention installed on a refrigerator 35 a portion of the refrigerator casing being broken away.

Figure 2 is a vertical section of the apparatus.

Figure 3 is a vertical section of a portion 40 of the apparatus on a larger scale.

Figure 4 is a somewhat diagrammatical representation of a plurality of seals in series.

Figure 5 is a vertical section of a modified 45 form of apparatus.

The apparatus, in its present form, comprises a refrigerant fluid compression element and a refrigerant fluid expansion element. The compressor element is substantially the same as that shown in my Patent 50 No. 1,373,175, dated March 29, 1921, and comprises a shell or casing 2, to the ends of which are secured the caps 3-4. Within the casing 2 is provided a helical passage or 55 conduit 5, which is coaxial with the casing

and which is preferably gradually reduced in area, or cross section, from its inlet end, which is adjacent the cap 3, to its outlet end, which is adjacent the cap 4. The passage 5 is preferably formed by a peripheral helical 60 groove or thread on the tubular body 6, which fits tightly within the casing 2. In practice it is preferable to provide two such helical passages arranged as a double thread.

The body 6 is hollow and secured in the body and projecting therefrom at the inlet end, is a pipe or conduit 7, which is of less diameter than the bore in the body so that an annular conduit or passage 8 is formed. The upper cap 4 is provided with an axial 70 cylindrical extension and a conduit or pipe 9, secured to the pipe 7 and forming a continuation thereof, extends well up into the cap extension. Surrounding and secured to the casing 2 is a refrigerant fluid cooling 75 tube or coil 12, the intake end 13 of which extends into the pipe 7 and passes through the wall thereof opening into the annular conduit 8. The cooled compressed fluid discharges from the coil through the tube 14 to 80 the expansion valve.

The compressor and expansion units are connected by the pipe or conduit 15, which at one end is secured to and passes through the cap 3 and which is secured at its other end to the cap 16, secured to the end of the casing 17, to which is secured the expansion coil 18. The compressor and expansion units are rigidly connected together, forming a single unit, which is adapted to be bodily 90 rotated about the axis of the shaft 19, but does not rotate on its own axis. The compressor-expansion unit is held at a considerable angle to the shaft 19, so that all parts of the apparatus move in circular paths, normal to the axis of the shaft 19. Journaled on the shaft 19, which is stationary and supported in the frame 21, is a frame 22, which is rotated about the shaft, by the motor 23, through the medium of the belt 24. In the 100 present construction, the shaft 19 is vertically disposed and the axis of the compressor-expansion unit is disposed at an angle to the vertical and for purposes of convenience will be so described in the specification, although 105 it is to be understood that the device is not limited, in its operation, to rotation about a vertical axis. The upper portion of the rotating frame 22 is provided with an arm 25 in which the cap 4 is journaled. The 110

connecting pipe 15 is also suitably journaled in the frame 22 at the lower portion thereof. The frame 22 is provided with a suitable counterweight 26 to balance the parts about the axis of the shaft 19.

The frame 21 is mounted on the top of the refrigerator 27 and the connecting pipe 15 passes through an aperture in the top of the refrigerator, so that the expansion coil 10 is disposed within a chamber 28 in the refrigerator. The aperture through the top of the refrigerator is conical in shape, to accommodate the bodily movement of the connecting pipe and the aperture surrounding the pipe 15 is closed by a crescent shaped block 29, secured to the lower end of the frame 22, so that passage of air through the aperture is restricted to a minimum.

The axis of the compressor-expansion 20 unit intersects the axis of the shaft 19 in the aperture in the top of the refrigerator, and a gimbal ring mounting 31 secures the pipe 15 to the refrigerator casing at this point, holding the compressor-expansion 25 unit against rotation about its axis. The apparatus is, therefore, movable bodily about a vertical axis, to which the axis of the body is inclined and through which it passes, so that points on the device at progressively 30 greater distance from the point of intersection, travel in circular paths of progressively greater radius.

The casing 17 is closed at its lower end by the plate 32 and the expansion coil 18 is connected at its intake end 33 to the lower end of the casing 17, and at its discharge end to the upper end of the casing. Arranged within the casing 17 and extending through the lower closing plate 32 is a pipe or 40 conduit 34, closed at its lower end by the cap 35 and provided at its upper end with a flaring portion 36, terminating in a cylindrical portion 37 of greater diameter than the tube. The angle of the flaring portion 45 with respect to the axis of the pipe is preferably the same as the angle of the axis of the whole unit to the axis of rotation. The cylindrical portion 37 is of less diameter than the casing 17, so 50 that an annular passage 38 is provided between the portion 37 and the casing 17. The discharge end 39 of the expansion coil 18 preferably opens into this cylindrical portion 37 so that any compressor-liquid which 55 may pass through the coil 18 is returned to the tube 34. Liquid refrigerant discharging from the end 39 of the coil 18 into the cylindrical portion 37, pours over the upper edge thereof and passes through the annular 60 passage 38, into the casing 17. The tube 14 enters the pipe 15 above the intersection of the axes and extends downward through the pipe 15 and pipe 34, to the seal valve adjacent the cap 35.

65 The apparatus is suitably charged with

compressor liquid, which is preferably mercury, and with refrigerant fluid, which is preferably sulphur dioxide, although other suitable refrigerant fluids may be employed. The refrigerant fluid is compressed, in the 70 compressor, and passes to the expansion unit, wherein it is expanded. The compressor and the expansion unit are each separately charged with mercury, the mercury in the compressor serving as the compressing liquid, 75 and the mercury in the expansion unit serving as the expansion valve or seal. With the apparatus in operation, and moving bodily in a circular path about the axis of the shaft 19, centrifugal force causes the mercury and 80 the refrigerant to assume the positions indicated in Figure 2, and the greater the angular motion of the mercury, the greater will be the pressure exerted by it. As the apparatus moves about its axis, separate 85 masses of mercury and refrigerant fluid will, under the action of centrifugal force, alternately enter the lower end of the passage 5 and the mercury will act to compress the intermediate bodies of refrigerant fluid 90 in the passage. The compressed fluid and mercury will discharge into the chamber below the cap 4 and the mercury, being heavier, will pass to the outer edge of the chamber and will flow up into the cap 4 95 and then down through the tube 9 into the chamber in the bottom of the casing 2, where it is again picked up by the passage 5. Sufficient mercury is charged into the 100 chamber to maintain a continual circulation thereof, through the passage 5 in separated masses and back through the tube 9. The compressed refrigerant fluid, which may be in gas or liquid form, is separated from the mercury in the upper chamber by 105 centrifugal force and passed downward through the annular passage 8, into the pipe 13 and thence into the cooling or condenser coil 12. The gas is condensed in the condenser coil, which rapidly radiates the released heat of vaporization of the refrigerant to the air or water spray in which the condenser coil moves. Due to the rotational movement of the apparatus, the condensed refrigerant is carried through the condenser 110 coil and is forced downward through the tube 14 to the lower end thereof, in the expansion unit. The pressure produced in the compressor is greater than the pressure limit of the valve seal and this excess of pressure 115 limit of the compressor over the pressure limit of the seal valve is always available to force the condensate through the condenser and into the tube 14. The seal tube 120 34 is charged with sufficient mercury so that when the apparatus is in motion, it remains full up to the commencement of the flare 36 as shown in Figure 2. This mass of mercury is displaced from the axis of rotation of the apparatus and exerts a down- 125 130

ward pressure on the cap 35 and an upward pressure against the descending compressed refrigerant in the tube 14. As the pressure in the tube 14 increases, the compressed refrigerant is forced down in the tube, displacing the mercury therein, and finally reaches the lower end of the tube 14, at which time the pressure on the refrigerant is equal to the pressure of the mercury 10 in the tube 34 and refrigerant liquid is released into the tube 34 and small drops of it rise through the tube 34 to the surface of the mercury therein. The refrigerant fluid discharges over the edge of the upper cylindrical portion 37 of the tube and enters the casing 17 mixing with the main body of liquid refrigerant therein. From this storage chamber in the casing 17 the refrigerant liquid passes through the outlet 33 into 20 the expansion coil 18, through which it is forced due to the operation of the machine. The liquid refrigerant is thus exposed to the surface of the expansion coil through which heat is absorbed from the surrounding medium, vaporizing the liquid or a portion thereof. The vapor, together with the unevaporated liquid refrigerant, is discharged back into the cylindrical chamber 37 at the connection 39. The vapor passes 25 from the chamber 37 through the pipe 15 into the low pressure chamber of the compressor.

Placed over and spaced from the upper end of the pipe 15 is a cap or baffle 41 which prevents the flow of any unnecessary mercury from the compressor, to the lower end of the machine, when the machine is stopped. While no harm would be done should the mercury fall down into the lower 40 part of the machine when at rest, it would be necessary to operate the machine for a brief time, to produce the proper distribution of the mercury. However, by a suitable design and position of the cap 41, a small 45 amount of mercury may be permitted to flow into the bottom part of the machine, every time it stops, simply to insure the presence of an adequate amount there when the machine is again started.

The surface of the sealing liquid is maintained at the flaring portion 36 of the seal tube 34 by means of a helical eliminating coil 42 having an open lower end and disposed within the cylindrical upper portion 55 37 of the seal tube. This coil, operating in the same manner as the compressor helix, picks up any liquid that is present at its intake end and carries it through, past the neutral center of the machine, discharging 60 it into the compressor end. The coil 42 has an upward extension 43 disposed parallel to the axis of the pipe 15 and extends upward in the pipe past the neutral center of the machine. It is apparent that both the sealing liquid and the liquid refrigerant will be

picked up by the eliminating coil 42, and should the liquid refrigerant be discharged into the low pressure side of the compressor, it would defeat the operation of the machine. This is prevented by a trap or seal 70 on the discharge end of the tube 43. The seal may comprise a return bend in the tube 43 or it may comprise a cartridge or closed upper end cylinder 44 surrounding the discharge end of the tube 43. The discharge 75 end of the cartridge is disposed above the neutral center of the machine, so that mercury, passing through the trap, is flowed into the compressor. The trap or seal fills with the denser sealing liquid and while permitting the passage of additional sealing liquid, 80 does not permit the passage of the less dense refrigerant liquid.

The pressure offered by the sealing liquid 85 in the tube 34, resulting from rotating the tube about the external axis, will prevent the refrigerant fluid from flowing through the sealing liquid, unless a greater pressure exists in the fluid. The amount of pressure difference which such an apparatus will 90 maintain depends upon the radial depth of the sealing liquid, the radial distance from its center of mass to the axis, and the speed of rotation of the vessel about the axis. Thus, any desired value of pressure reduction 95 may be provided by such an apparatus and various quantities of fluid, either liquid or gas, may be passed from the higher to the lower pressure.

The refrigerant vapor is condensed to 100 liquid form in the condenser coil 12 and the pressure of the vapor in the coil varies with the amount of condensate therein. As condensate accumulates in the condenser coil, the heat radiating surface to which the vapor 105 is exposed becomes less, resulting in an increase in pressure in the coil and causing a charge of the condensate to be forced through the seal valve. The discharge of this condensate increases the condenser surface, thus 110 lowering the pressure in the condenser and automatically stopping further flow of refrigerant through the seal until the pressure again builds up.

If desired, a number of seals may be used. 115 in series, as shown in Figure 4, each partially reducing the pressure. In this way, a smaller and more compact design is possible as the multiplicity of small seals permits smaller radii to be used on each seal than 120 would be required on a single equivalent seal. The liquid under pressure first discharges through the seal 45, where the pressure is partly reduced, then passes through the seal 46, further reducing the pressure, 125 and then through the seal 47 to the low pressure receiver.

I have found that in many instances, particularly in smaller sizes of the apparatus, 130 that the expansion coil may be eliminated,

depending on the storage chamber to act alone as the expansion space. This modified form of apparatus is shown in Figure 5 wherein the storage chamber 52 is made 5 larger in diameter, so that it presents a larger heat transferring surface, which may be ribbed or otherwise formed to further increase its area. In this construction, the 10 eliminator coil 53 instead of being arranged to pick up mercury from the seal tube, is disposed within the storage chamber 52, with its lower end so disposed that it will pick up any mercury which finds its way into the storage chamber and deliver it to 15 the compressor. In this construction I have also shown a modified form of eliminator tube discharge. Instead of being provided with a mercury trap, as shown in Figure 3, the discharge tube 43 extends into the mercury 20 in the tube 7 of the compressor, forming a mercury seal which prevents liquid refrigerant from passing up into the compressor.

In this construction also, I have found 25 that the gimbal ring may be dispensed with and flexible straps 54 employed for preventing rotation of the device about its own axis while permitting rotation about the external axis.

30 I claim:

1. Means for restraining the flow of fluid comprising the combination with a vessel 35 adapted to be moved in a circle about an upright axis and containing high and low pressure spaces, of a body of dense liquid therein adapted to be held in a position remote from said axis during the movement of the vessel and separating said high and low pressure spaces, and means for introducing 40 a less dense fluid from the high pressure side into the liquid near the bottom thereof.

2. Means for restraining the flow of fluid 45 from a compressor to an expansion space comprising the combination with a vessel and means for revolving it about an axis inclined to its own axis, of a quantity of liquid in said vessel held outward by centrifugal force during the movement of the vessel, and retained in a position separating 50 high and low pressure spaces therein, and means for causing the fluid from the high pressure space to pass into said liquid at a point remote from said axis.

3. The combination with an inclined tube 55 mounted for rotation about an axis inclined to the axis of the tube, of a quantity of mercury retained in said tube, and means for introducing fluid under pressure into said tube and below the surface of the mercury 60 therein during the rotation of the tube.

4. Means for restraining the flow of fluid 65 comprising the combination with a tube mounted for rotation about an axis and at an angle thereto, of a quantity of liquid retained in said tube and adapted to exert

centrifugal pressure on the end of the tube remote from said axis during rotation of the tube, means for introducing the fluid under pressure into said liquid adjacent the end of the tube whereby said fluid passes through 70 the liquid and means automatically maintaining a predetermined minimum quantity of liquid in said tube.

5. The combination with a tube adapted 75 to be rotated about an axis remote from the axis of the tube and at an angle thereto, of a quantity of liquid in said tube adapted to exert pressure on the end of the tube remote from the axis of rotation during rotation of the tube about said axis of rotation, means 80 for compressing fluid and introducing said fluid under pressure into said liquid adjacent the end of the tube remote from the axis, and a helical tube for conveying excess liquid from the first tube to said compressing means.

6. The combination with a tube adapted 85 to be rotated about an axis remote from the axis of the tube and at an angle thereto, of a quantity of liquid in said tube adapted to exert pressure on the end of the tube remote from the axis of rotation during rotation of the tube about said axis of rotation, means 90 for introducing fluid under pressure into said liquid adjacent the end of the tube remote from the axis, a chamber receiving said fluid from said tube and a helical tube arranged within and coaxial with said chamber and having its lower open end disposed in said chamber at a point remote from the 100 axis of rotation thereof.

7. The combination with a tube adapted 105 to be rotated about an axis remote from the axis of the tube and at an angle thereto, of a quantity of liquid in said tube adapted to exert pressure on the end of the tube remote from the axis of rotation during rotation of the tube about said axis of rotation, means 110 for introducing fluid under pressure into said liquid adjacent the end of the tube remote from the axis, a chamber surrounding said tube and receiving fluid and liquid therefrom, a helical tube arranged within said chamber and having its lower open end disposed at a point remote from the axis of 115 rotation thereof, and a trap in said helical tube operating to prevent the flow of fluid therethrough, while permitting the flow of the liquid therethrough.

8. The combination with a tube adapted 120 to be rotated about an axis remote from the axis of the tube and at an angle thereto, of a quantity of liquid in said tube adapted to exert pressure on the end of the tube remote from the axis of rotation during rotation of the tube about said axis of rotation, means 125 for introducing fluid under pressure into said liquid adjacent the end of the tube remote from the axis, a chamber surrounding said tube and receiving fluid and liquid 130

therefrom, a tube for removing liquid from said chamber and means for preventing the flow of fluid through said second tube.

9. The combination with means for compressing and condensing a vapor, a passage for the condensate, a valve means imposing a restriction to the outflow of the condensate, constituted of a body of denser liquid retained in said passage, an expansion space 65 for the fluid escaping through said liquid, and a conduit for conveying the expanded fluid back to the compressor.

10. The combination of a fluid compressor, an expansion chamber rigidly connected thereto and mounted to rotate therewith, a conduit connecting the high pressure side of the compressor to said chamber, a valve in said conduit for controlling the flow of compressed fluid and reducing its pressure 70 before entry into said chamber, said valve consisting of a body of liquid denser than said fluid retained in said conduit under centrifugal pressure, and a conduit for the expanded fluid connecting the chamber with the low pressure side of the compressor. 75

11. The combination of a fluid compressor in an upper position containing a compressor liquid, a lower expansion chamber having a valve for the compressed fluid constituted of a portion of said liquid, means for rotating said parts, and means for limiting the flow of compressor liquid toward the expansion chamber when said parts come to rest. 80

12. The combination of a revolving compressor, a condenser, an expansion chamber, means for conducting condensed compressed fluid from the condenser to the expansion chamber, including a vessel and a quantity 85 of liquid in said vessel through which said compressed condensed fluid passes, said liquid being forced outward by centrifugal force to oppose the flow of the fluid.

13. The combination of a compressor, a condenser, an expansion chamber, and means for conducting the compressed condensed fluid from the compressor to the expansion chamber, including a vessel arranged to rotate about an axis remote from the axis 90 of the vessel, and a quantity of dense liquid in said vessel forced outward by centrifugal force and opposing the flow of the compressed fluid. 100

14. The combination of a fluid compressor, means for supporting it for rotation about an upright axis and at an oblique angle to said axis, a supply conduit leading fluid to be compressed upwardly to the low pressure side of said compressor, a second conduit 105 leading the compressed fluid downwardly

from the high pressure side of said compressor to an expansion space, a compressor liquid in said compressor and means for preventing flow of said liquid into the said supply conduit when the rotation ceases. 110

15. The combination with a casing, of a fluid compressor mounted on the casing and adapted to be moved in a circle about an axis inclined to the axis of the compressor, an expansion chamber arranged within the 70 casing, a conduit passing through the wall of the casing and rigidly connecting said compressor and expansion chamber, and a conduit for conveying the compressed fluid from the compressor to the expansion chamber. 75

16. The combination with a closed casing, of an expansion chamber in said casing arranged to rotate about an axis remote from its own axis, a compressor secured to said chamber and rotatable therewith and arranged externally of the casing, a conduit connecting the high pressure side of the compressor with the expansion chamber, a chamber interposed in said conduit and carried by the expansion chamber, and a quantity of relatively dense liquid in said second chamber through which the compressed fluid passes. 80 85

17. The combination with a compressor and an expansion chamber disposed on an axis inclined to and intersecting an axis of rotation with the compressor arranged on one side of said intersection and the expansion chamber arranged on the other side 90 of said intersection, of a liquid seal arranged adjacent the expansion chamber for controlling the flow of fluid from the compressor to the expansion chamber. 95

18. The combination with a fluid compressor employing mercury as the compressing agent, of an expansion chamber, a conduit connecting the compressor and the expansion chamber, a mercury seal in said conduit 100 for controlling the flow of fluid from the compressor to the expansion chamber and means for returning to the compressor any excess mercury in the seal. 105

19. The combination with a casing, of a fluid compressor, a fluid expansion device 110 both mounted on the casing with the fluid expansion unit enclosed within the casing and the fluid compressor unit exposed to the atmosphere, and means for rotating said device about an axis inclined to the axis of the device. 115

In testimony whereof, I have hereunto set my hand at San Francisco, California, this 3d day of November, 1919.

JAY GRANT DE REMER.
